[57] CLAIM

The ornamental design for an automobile roof mounted stereo, as shown and described.

DESCRIPTION

FIG. 1 is a perspective view of an automobile roof mounted stereo showing my new design; the broken line showing of the truck is for illustrative purposes only and forms no part of the claimed design.

FIG. 2 is a front elevational view thereof.

FIG. 3 is a rear elevational view thereof.

FIG. 4 is a top plan view of the automobile roof mounted stereo the bottom plan view being a mirror image of the top plan view; and,

FIG. 5 is a left side elevational view thereof, the right side elevational view being a mirror image of the right side view.
